UNITED STATES PATENT OFFICE.

MARIE HEILBRON AND JEROME W. WALKER, OF NEW YORK, N. Y.

MACHINE FOR OPENING LETTERS.

No. 895,087.

Specification of Letters Patent.

Patented Aug. 4, 1908.

Application filed November 11, 1907. Serial No. 401,558.

To all whom it may concern:

Be it known that we, MARIE HEILBRON and JEROME W. WALKER, citizens of the United States, and residents of New York city, in the county of New York and State of New York, have invented certain new and useful Improvements in Machines for Opening Letters, of which the following is a specification.

- 9 The invention relates to improvements in machines for opening letters, and it consists in the novel features and combinations of parts hereinafter described, and particularly pointed out in the claims.
- 5 The object of the invention is to provide an efficient machine capable of convenient operation for rapidly removing one or more edges of sealed envelopes caused, in banks or compact bundles, to travel along the bed-plate of the same, thereby opening said envelopes and permitting of the convenient and rapid removal of the letters therefrom, and to this end the machine of our invention comprises a horizontal bed-plate, an oblique cutting-roller mounted therein and projecting slightly above the surface of the same, a novel clamping-frame for holding the envelopes banked together on edge on said bed-plate and permitting them to be moved over and against said cutting-roller, and means for rotating said roller. The oblique cutting roller is spirally cross-grooved to create an effective cutting surface thereon. If preferred the machine may also be provided with a vertical cutting-roller to remove one end edge of the envelopes while the horizontal oblique roller is cutting off one longitudinal edge thereof.

The invention will be fully understood from the detailed description hereinafter presented, reference being had to the accompanying drawings, in which:

- 5 Figure 1 is a top view of a machine constructed in accordance with and embodying the invention; Fig. 2 is a side elevation, partly broken away, of the same and illustrates by dotted lines a bank of envelopes set on edge on the bed plate of the machine and clamped by the front clamping plate against the rear clamping plate preparatory to the bank of envelopes being pushed rearwardly or toward the left, looking at Figs. 1 and 2, over the oblique cutting roller; Fig. 3 is an end view, partly broken away, of the same; Fig. 4 is an enlarged detached view of a portion of the machine, the same being

partly in section on the dotted line 4—4 of Fig. 1, the cutting rollers and their intermeshing gear wheels and shafts being represented in side elevation and the section 60 being through one side portion of the frame of the machine and through one set of the rods provided for supporting and guiding the clamping plates; Fig. 5 is a detached side elevation of a detail of the machine and is 65 presented to indicate that the bearings of the oblique roller may be made vertically adjustable so as to project the cutting surface of the roller to a greater or less extent above the bed-plate of the machine; Fig. 6 is a 70 front end view of a portion of the machine and is presented to illustrate the latch by which the front clamping plate is normally held in its outer position; and Fig. 7 is a longitudinal section through one set of the 75 rods provided for supporting and guiding the clamping plates.

In the drawings 10 designates the bed-plate of the machine, 11 end supporting legs or frames therefor, 12 an oblique cutting 80 roller mounted in the frame of the machine and projecting upwardly to a slight extent through an oblique slot 14 in said bed-plate, 15 an electric motor for driving said roller, 16 an auxiliary vertical roller geared to the 85 roller 12 and used for removing an end edge of the envelopes when desired, 17 a box for collecting the paper dust arising from the action of the roller 12 against the envelopes, 18 an inner clamping plate against which the 90 envelopes may be banked on edge, and 19 an outer clamping plate to engage the outer face of the bank of envelopes, the plate 18 being secured on the forward ends of longitudinally 95 slidable rods 20 and the plate 19 on the forward ends of longitudinally slidable rods 21 adapted to telescope into the rods 20.

The bed-plate 10 presents a substantially flat upper surface and has mounted upon its rear end the bearing and guiding sleeves 22 100 for the rods 20, which are preferably formed of tubing, and, as hereinbefore explained, carry upon their front ends the transverse clamping plate 18. Upon the rear ends of the rods 20 are secured collars 23 which limit 105 the forward movement of said rods. The plate 18 carried by the rods 20 is recessed on its lower edge to pass by without touching the roller 12 and on its side edge to pass by without touching the roller 16. The clamping plate 19 corresponds exactly with the plate 18 and is arranged parallel therewith,

said plate 19 being secured upon the front ends of the rods 21 which have their rear ends mounted within the tubular rods 20 and are normally given a spring tension toward the rear by means of coiled springs 24 (Fig. 7) arranged within the rods 20, 21, and secured at one end to plugs at the rear ends of the rods 20 and at the other end to plugs at the front ends of the rods 21. The purpose of the springs 24 is to cause the said plate 19, when released, to slide toward the plate 18 and against the bank of envelopes, indicated at 25, as shown in Fig. 2. I preferably provide the plate 19 with a handle 26 and equip the machine with latch mechanism for holding the plate 19 in its outer position shown in Fig. 1, said latch mechanism comprising, as shown more clearly in Fig. 6, a pivoted latch 27 adapted to engage a catch or hook 28, the latter being preferably on the plate 19 and the latch on the end of the bed plate 10. The tubular rods 20 guide the rods 21 and are themselves guided by the bearing sleeves 22, and in the employment of the machine the rods 21 when the latch 27 is released telescope into the rods 20 to carry the plate 19 against the bank of envelopes, as illustrated in Fig. 2, and then the operator grasping the handle 26 will push the rods 21, 22 with the bank of envelopes between the plates 18, 19 rearwardly over the bed plate of the machine, the rods 20 at such time sliding rearwardly through the sleeves 22.

The roller 12 is spirally cross-grooved to form an effective cutting surface thereon and is, with its shaft 29, obliquely mounted, and said shaft has on its outer end a belt wheel 30 whereby power from the motor 15 may be communicated through a belt 31 to the roller 12. The upper surface of the roller 12 projects very slightly through the oblique slot 14 in the bed plate, and below said roller is arranged the box 17 to catch the paper dust from said roller. The box 17 is a plain ordinary box having its bottom 32 in the form of a sliding door supported on the lugs 33.

There are two features with respect to the roller 12 which we consider of great importance, one being that the roller is set obliquely to the path of the bank of envelopes and the other that said roller is spirally cross-grooved to form the cutting surface. The oblique position of the roller 12 enables said roller in a superior manner to remove the edges of the envelopes carried against it and also prevents the projecting downwardly into the slot 14 of the lower edge of any of the envelopes during the travel of the latter or during any period that the bank of envelopes might be over said roller. The spiral cross-grooves of the roller 12 increase the efficiency of the roller. The oblique position of the roller, whether the latter be spirally cross-grooved or otherwise given its cutting surface, is of very great importance. The vertical roller 16 is also spi-

rally cross-grooved and it is intended for use in removing an end edge from the bank of envelopes 25. The roller 16 is connected by gear wheels 34 with the shaft of the roller 12 and the bank of envelopes while passing over the roller 12 will have one end edge carried against the roller 16. The roller 16 is not a necessary part of the machine but is useful in the event that it should be desired to open two edges of the envelopes in lieu of one edge thereof.

In the employment of the machine, the plate 19 will be drawn to its front position shown in Fig. 1 and secured by the latch 27, and thereupon the envelopes will be banked, so on edge, on the bed plate 10 between the clamping plates 18, 19. After a suitable quantity of the envelopes have been thus arranged on the bed plate the latch 27 will be moved to release the plate 19, and thereupon the springs 24 will move said plate against the bank of envelopes, after which, the motor 15 being in action, the attendant will grasp the handle 26 and push the clamping-plates, envelopes and rods 20 rearwardly, thereby moving the envelopes over the roller 12 and against the roller 16, with the result that said rollers will open the envelopes at two of their edges. The envelopes should be pressed downwardly with some firmness upon the bed plate 10 so that their lower edges may uniformly engage said plate and be acted upon by the roller 12, and when the vertical roller 16 is made use of the end edges of the envelopes at one end of the bank should be moved firmly against the vertical guide plate 35 so that said edges may be carried uniformly against the roller 16, whose edge will project slightly through a slot in said plate 35. The plate 35 may be cast upon the bed plate 10.

Fig. 5 is presented to illustrate the shaft 29 as mounted at its ends in bearing blocks 36 set into slots in the machine frame and rendered vertically adjustable by means of screws 37. The roller 12 will be adjusted or "set" so as to remove only a thin edge portion of the envelopes and omit to cut deeply into the same. The spiral cross-grooves in the roller create small sharp points, each of which removes only an infinitesimal portion of an edge of the envelop, but all of which co-operate, during the operation of the machine, in removing the entire edge of the envelop, said cutting points acting one after another during the travel of the envelopes over and against the roller.

What we claim as our invention and desire to secure by Letters-Patent, is:

1. In a machine for opening letters, a bed plate upon which the letters may be banked on edge and which is adapted to have the letters move along the same, and a rotary oblique cutting roller in the path of the letters, said bed plate being slotted to expose a sur-

face of the roller to the edge of the letters moved along the same; substantially as set forth.

2. In a machine for opening letters, a bed plate upon which the letters may be banked on edge and which is adapted to have the letters move along the same, and a rotary oblique cutting roller in the path of the letters, said bed plate being slotted to expose a surface of the roller to the edge of the letters moved along the same, and said roller being spirally cross-grooved to form a cutting surface thereon; substantially as set forth.

3. In a machine for opening letters, a bed plate upon which the letters are to be banked on edge, a rotary oblique cutting roller in the path of the letters, and clamping means with which to move the bank of letters along said bed plate and over said roller, said bed plate being slotted to expose a surface of the roller to the edge of the letters; substantially as set forth.

4. In a machine for opening letters, a bed plate upon which the letters are to be banked on edge, means for alining the end edges of the letters at one end of the bank, a rotary cutting roller in the path of said end edge of the letters, and clamping means for holding the letters compactly and permitting their movement over the bed plate of the machine and against said roller; substantially as set forth.

5. In a machine for opening letters, a bed

plate upon which the letters are to be banked on edge, a rotary oblique cutting roller projected slightly through said bed plate in the path of the letters, a vertical cutting roller in the path of one edge of the bank of letters, and clamping means with which to move the bank of letters along said bed plate and against said rollers; substantially as set forth.

6. In a machine for opening letters, a bed plate upon which the letters are to be banked on edge, an oblique cutting roller projecting slightly through said bed plate in the path of the letters, and clamping means for engaging the letters and permitting them to be moved against said roller, said clamping means comprising rods slidably mounted over said bed plate, a clamping plate secured to said rods, rods telescoping with the aforesaid rods and having on their forward portions a clamping plate, springs normally acting to move said last-mentioned plate against the letters, and latch mechanism for holding said plate stationary in opposition to the force of said springs; substantially as set forth.

Signed at New York city, in the county of New York, and State of New York, this 6th day of November, A. D. 1907.

MARIE HEILBORN.
